UNITED STATES PATENT OFFICE.

JAMES M. HUGHES, OF ASHLAND, AND JEHU D. WILLIAMS, OF DENTON,
KENTUCKY.

DUMPING-CAR.

SPECIFICATION forming part of Letters Patent No. 378,368, dated February 21, 1888.

Application filed October 10, 1887. Serial No. 251,890. (No model.)

To all whom it may concern:

Be it known that we, JAMES M. HUGHES and JEHU D. WILLIAMS, citizens of the United States, residing at Ashland and Denton, in the 5 counties of Boyd and Carter, respectively, and State of Kentucky, have invented certain new and useful Improvements in Dumping-Cars; and we do hereby declare the following to be a full, clear, and exact description of the invention, such as will enable others skilled in the art to which it appertains to make and use the same.

This invention relates to dumping-cars; and it has for its object to provide a simply-constructed, easily-operated, and durable car, by which the contents of the body or bed of the car may be readily dumped on either or both sides of the track, as desired; and it consists of the parts and combinations of parts hereinafter described and claimed.

In the accompanying drawings, forming a part of this specification, Figure 1 is a perspective view of our improved car, with one bed removed and the other in a dumping position; Fig. 2, an end elevation showing one bed in a dumping position; Fig. 3, a side elevation; Fig. 4, a plan view with bed removed; Fig. 5, a view of the bottom of one of the beds; Fig. 6, a detail perspective view of the locking device, and Figs. 7 and 8 detail views.

Similar letters refer to similar parts throughout the several views.

Although our invention will be herein described in connection with a hand-car, we desire it understood that we may apply it to a flat car for hauling freight, such as stone, sand, coal, &c., or to a construction-car.

A represents the wheels, B the side beams, and C the cross-beams, of an ordinary hand-car with our improvements thereon. Cross-bars *a'*, for binding the side beams to the cross-beams, are bolted at each end of the car.

On the cross-beams C we rigidly secure, by means of bolts, beams D, having their ends inclined, as at *a*, and to these inclined ends we bolt hooked bearing-irons *b*, so that the upper edges of their hooked ends will be flush, or nearly so, with the upper surface of the beams D. To the bottom of the bed or body E of the car a beam, *c*, is secured, and to this beam a bar, *d*, is attached by means of the strap-irons

e, which are bolted on each side of the bar to said beam *c*. The bars rest in the hook-irons *b*, so as to form a hinge-joint, and the cars turn thereon when dumped, as clearly shown 55 in Figs. 1 and 2. To prevent the cars or beds being turned completely over in dumping, one end of a chain, *f*, is attached to the bottom of the car near its center, longitudinally, and its other end passes through a perforation, *s*, in a 60 longitudinal beam, F, which is secured between the cross-beams C and D, and, as shown in Fig. 8, is secured to an eyebolt, *g*, between washers on which a spiral spring, *h*, is mounted to deaden the jar of the bed when it is dumped. 65 The beds E, as clearly shown in Fig. 2, occupy only about one-half the hand-car, and are provided with handles *i*, for dumping them and for returning them to their position on the hand-car after they are emptied. They are 70 also provided with a sliding gate, *m*, of any desired or known construction.

To the rear sides of the beds E, at their bottoms, is attached a series of spring-catches, *n*, as many as desired, and to the bar H, which 75 is secured to the beams D, a series of rigid catches, *o*, are secured, corresponding in number and position to the catches *n*. Immediately below the bar H a rod, K, is journaled in any suitable manner in the beams D, and 80 carries a series of eccentrics, *p*, corresponding in number and position to the spring-catches *n*, the eccentrics being secured to the bar by thumb-screws, so as to be easily adjusted thereon, and to either or both ends of the bar 85 a lever, *r*, is secured.

There may be any desired number of beds on a car, from one to six on a side, and the eccentrics may be adjusted to dump one or all of them at once on one side and then turned 90 to dump the other side.

The device can be attached to any railway flat car or hand-car, and can be removed in a few moments without defacing the car in the least, so that the car may be used for any other 95 purpose; and, further, the device can be applied to either or both ends of a car, so as to dump in the front or rear.

Having thus described our invention, what we claim as new, and desire to secure by Letters 100 Patent, is—

1. The combination, in a dumping-car, of

the beams D, having the inclined ends, the hook-irons b, secured thereto, the beams F, having perforations s, the chains f, eyebolts g, spiral springs h, the beds E, strap-irons e, bars 5 d, and means for locking the beds to the frame of the car, substantially as described.

2. The combination, in a dumping-car, of the beams D, having inclined ends, the hook-irons b, the beams F, having perforations s, 10 the chains f, the eyebolts g, springs h, strap-irons e, bars d, the spring-catches n, the bar

H, having the catches o attached thereto, the rod K, adjustable eccentrics p, and lever r, substantially as described.

In testimony whereof we affix our signatures 15 in presence of two witnesses.

JAMES M. HUGHES.
JEHU D. WILLIAMS.
